UNITED STATES PATENT OFFICE.

MARTIN OVERLACH, DECEASED, LATE OF CHARLOTTENBURG, BY META OVERLACH, OF CHARLOTTENBURG, HEIRESS, AND MORITZ KÖRNER, OF BERLIN, GERMANY, ASSIGNORS TO THEODOR TEICHGRAEBER, OF BERLIN, GERMANY, A FIRM, AND SACCHARINFABRIK AKTIENGESELLSCHAFT, VORM. FAHLBERG, LIST & CO., OF SALBKE-WESTERHÜSEN, GERMANY, A FIRM.

COCAIN ISOVALERIANATE.

1,120,233.

Specification of Letters Patent. Patented Dec. 8, 1914.

No Drawing.

Application filed September 6, 1912. Serial No. 719,031.

To all whom it may concern:

Be it known that MARTIN OVERLACH, late a subject of the German Emperor, and resident of Charlottenburg, near Berlin, in the 5 Kingdom of Prussia, German Empire, deceased, and MORITZ KÖRNER, a subject of the German Emperor, and resident of Berlin, in the Kingdom of Prussia, German Empire, have invented new and useful Im- 10 provements in Cocain Isovalerianate, of which the following is a full, clear, and exact specification.

This invention relates to a new alkaloid salt, viz., cocaine isovalerianate.

15 The hitherto unknown cocaine isovalerianate has a number of important advantages over free isovalerianic acid and other isovalerianates for medical purposes.

20 Isovalerianic acid itself as well as its salts, cannot be used for subcutaneous injection, as when they are injected, violent burning pain is produced and moreover there is a mechanical caustic action exercised on the subcutaneous tissue producing 25 necrosis at the point of injection. This disadvantage which hitherto prevented isovalerianic acid from being introduced directly into the living tissues of the body, is completely avoided by binding the acid to cocaine, as burning pain is thereby avoided, and a mechanical combustion or necrosis 30 prevented. Cocain isovalerianate has however a further advantage that the dose of isovalerianic acid can be increased. The 35 preparations hitherto known in which isovalerianic acid was bound to alkaloids, could not be used for injection, for apart from the disadvantage already mentioned, the dose of isovalerianic acid that could be

40 used was too small, in order to insure completely the tonic effect of isovalerianic acid on the nerves, as otherwise the dose of the base combined with it, became too large. In that respect also cocaine isovalerianate 45 removes the existing disadvantages as it makes it possible to combine it with isovalerianic salts of other bases, the action of

cocain isovalerianate as regards the removal of burning pain and necrosis being sufficient to render isovalerianic acid bound to the 50 other bases innocuous also in that respect. It therefore becomes possible in that way to introduce into the body by subcutaneous injection such bases together with isovalerianic acid, the influence of which on the 55 organism is to be modified by the presence of isovalerianic acid. Isovalerianic salts of various alkaloids could be used, which supplement the action of each other, the unpleasant by-effects of one being counter- 60 acted by the other, and their favorable action being combined with the favorable action of isovalerianic acid. All these results can be obtained only owing to the above mentioned valuable properties of cocaine isovalerianate. It is especially possible to prepare in this way a composition which combines the pain relieving action of morphin with the appeasing action of isovalerianic acid, by mixing isovalerianates of morphin, caffein and cocaine in suitable proportions. By the combination of these three 70 salts, it becomes for the first time possible to manufacture a preparation suitable for subcutaneous injection, in which the complete pain-relieving action of morphin is combined to the full extent with the tonic 75 action of isovalerianic acid on the nerves, without the appearance of injurious actions of morphin on the heart, breathing center 80 and the digestive organs, and the injurious actions which hitherto made impossible subcutaneous injection of isovalerianic acid preparations.

Injurious actions of morphin, which 85 hitherto was generally used as hydro-chlorid of morphin are of various kinds. First of all, it is not only the generally unpleasant consequences, but also the dangerous action of morphin on the heart, breathing 90 center and digestive organs, and on the other hand, owing to the presence of hydro-chloric acid, there is the possibility that chloro-morphid and apomorphin which are

much more poisonous than the original substance, would be formed.

The general injurious effects of morphin are avoided in the product according to this invention, by the caffeine neutralizing the paralyzing effect of morphin by its stimulating action. Moreover, due to the supporting effect of the cocaine, which is one of the best anti-vomitive means, the well-known disturbances of the digestive organs and continuous sickness which frequently appear when morphin is used are obviated.

The possibility of the formation of chloromorphid and apomorphin is prevented by the present preparation making it unnecessary to use morphin in the form of hydrochlorid and enabling it to be used as isovalerianate. Isovalerianic acid in its turn counteracts the injurious effects of morphin. Its use in a preparation for subcutaneous injection is however rendered possible only by the simultaneous use of cocaine isovalerianate. The latter does away with the very strong burning pain which otherwise always appears in case of subcutaneous injection of isovalerianic acid preparations, and with the caustic action on the subcutaneous tissue leading to necrosis, to such an extent that injurious effects in that direction of isovalerianic acid combined with the other bases, are also counteracted at the same time. In that way, it is possible to introduce a sufficient quantity of isovalerianic acid into the body by subcutaneous injection, without causing any injury by the introduction of such large quantity of base as would be required for binding such a great quantity of isovalerianic acid, as would be the case if isovalerianic acid were used bound only to one base, the quantity of which would then become too great for subcutaneous injection. The combination described therefore makes it possible first of all to utilize completely the desired tonic action of isovalerianic acid by subcutaneous injection, and on the other hand to obviate injurious by-effects of morphin while fully keeping its desired properties, by the counter effect of caffeine, cocaine and isovalerianic acid, and by the impossibility of formation of poisonous derivatives such as chloromorphid and apomorphin which are easily produced in case of hydrochlorid of morphin.

In preparing cocaine isovalerianate we proceed as follows.

First method: Equi-molecular quantities of cocaine base and isovalerianic acid, or a small excess of the latter are brought together, dissolved either both in ether, acetone or any other solvent, or only one of the two compounds is dissolved, and the other is introduced as it is, whereupon the solvent is removed by a slight heat, preferably in a vacuum. The two bodies could also be heat-

ed together in a pure state in equal molecular quantities, until the liquefaction of the cocaine indicated the end of the reaction. In any case, after the cooling, a syrup-like liquid is obtained from which after a certain time needles begin to separate. After standing for a long time, the product forms a thick mass of crystal needles. For the purpose of further purification, these crystal needles are rubbed with a little ethyl-ether in which the salt is soluble only to a slight extent. The amorphous parts then become crystalline. Petroleum ether is then added, in which the salt is practically insoluble, until the precipitation is completed. The salt is then removed and washed with petroleum ether.

1st example: 30.3 gr. of cocaine are heated with 11 gr. of isovalerianic acid, in a water bath, until liquid. After the cooling, 50 cubic centimeters of ethyl-ether are added, and the whole is stirred until the mass is of uniform solidity. Thereupon 100 gr. of petroleum ether of the specific gravity of 0.640 are added, the whole is left to stand for a short time, filtered, washed with a little petroleum ether and dried in a vacuum over sulfuric acid. The salt is obtained practically in a theoretical yield, in the form of fine, white needles which begin to melt at 125° and have a distinct smell of isovalerianic acid. They are soluble in water and alcohol, little soluble in ether and practically insoluble in petroleum-ether.

Second method: Instead of causing the free base and the free acid to act on each other, a cocaine salt could be of course brought together with an isovalerianate in a solvent, in which the acid of the cocaine salt gives an insoluble compound with the base of the isovalerianate and after filtering off the latter, the cocaine isovalerianate could be separated in a suitable manner. For instance, isovalerianate of barium could be dissolved in water, and an aqueous solution of sulfate of cocaine added in equal molecular quantities. Sulfate of barium is precipitated, while the isovalerianate of cocaine remains in solution, and after the filtering off, can be obtained by careful evaporation, preferably in a high vacuum. The syrup thus obtained, is converted into crystalline salt in the manner above referred to.

2nd example: 10 gr. of isovalerianate of barium are dissolved in 100 gr. of warm distilled water, and 11.8 gr. of sulfate of cocaine dissolved in 50 cubic centimeters of water, are added with stirring. After standing for some time, the substance is carefully filtered off from the barium sulfate, and the solvents evaporated at about 10 mm. pressure. The remaining syrup is dried for 24 hours in a vacuum over sulfuric acid and converted in the manner described into

crystalline salt which has the same composition as that obtained in the Example 1, and is obtained in a good yield.

What we claim is:—

5 The herein described cocaine isovalerianate, crystallizing in the form of fine, white needles which begin to melt at 125° and are soluble in water and alcohol, little soluble in ether and practically insoluble in 10 petroleum-ether.

In testimony, that we META OVERLACH and MORITZ KÖRNER claim the foregoing as the

invention of MARTIN OVERLACH, deceased, and MORITZ KÖRNER, we have signed our names in presence of two subscribing witnesses.

META OVERLACH,

*Executrix of the last will and testament of
Martin Overlach, deceased.*

MORITZ KÖRNER.
